DESIGN FOR A TWO-PIECE HAIR ORNAMENT

Joseph Halpern, New York, N. Y.

Application September 18, 1945, Serial No. 122,159

Term of patent 7 years

(Cl. D86—10)

To all whom it may concern:

Be it known that I, Joseph Halpern, a citizen of the United States of America, residing in New York city, county of Bronx, and State of New York, have invented a new, original, and ornamental Design for a Two-Piece Hair Ornament, of which the following is a specification, reference being had to the accompanying drawing, forming part thereof, wherein, piece hair ornament showing my new design in assembled position.

I claim:

The ornamental design for a two-piece hair ornament, substantially as shown.

JOSEPH HALPERN.
